UNITED STATES PATENT OFFICE

152,188

DESIGN FOR A COMBINED TURN SIGNAL, EXTREMITY MARKER, AND REARVIEW MIRROR

Thomas L. Dalton, Kansas City, Mo.

Application February 26, 1947, Serial No. 137,178

Term of patent 14 years

(Cl. D72—1)

To all whom it may concern:

Be it known that I, Thomas L. Dalton, a citizen of the United States, residing at Kansas City, in the county of Jackson and State of Missouri, have invented a new, original, and ornamental Design for Combined Turn Signal, Extremity Marker, and Rearview Mirror, of which the following is a specification, reference being had to the accompanying drawing, forming part thereof.

Fig. 1 is a rear elevational view of a combined turn signal, extremity marker, and rearview mirror showing my new design.

Fig. 2 is a perspective view thereof.

Fig. 3 is an elevation of the inner end thereof.

Fig. 4 is a front elevation.

Fig. 5 is an elevation of the outer end, and

Fig. 6 is a plan view.

I claim:

The ornamental design for a combined turn signal, extremity marker, and rearview mirror, as shown.

THOMAS L. DALTON.
